UNITED STATES PATENT OFFICE.

JUSTUS R. KINNEY, OF BOSTON, MASSACHUSETTS.

ROTARY PUMP.

Application filed July 23, 1923. Serial No. 653,095.

To all whom it may concern:

Be it known that I, JUSTUS R. KINNEY, a citizen of the United States of America, and a resident of Boston, in the county of Suffolk and State of Massachusetts, have invented certain new and useful Improvements in Rotary Pumps, of which the following is a specification.

This invention relates to rotary pumps and has for its object the production of a pump of this character in which the pump casing is provided with an annular passage communicating with the inlet and outlet, and in which passage one or more blades are adapted to travel and carry the liquid from said inlet to said outlet.

The invention consists in certain novel features of construction and arrangement of parts which will be understood readily by reference to the description of the drawings, and to the claims to be hereinafter given.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of the instrumentalities as herein shown and described, except as required by the scope of the appended claims.

Of the drawings:

Figure 1 represents a longitudinal vertical section of a pump embodying the principles of the present invention.

Figure 2 represents a vertical section of same on line 2, 2 on Fig. 1,

Figure 3 represents a vertical section of same on line 3, 3 on Fig. 1,

Figure 4 represents a vertical section of same on line 4, 4 on Fig. 1, and

Figure 5 represents a vertical section on line 5, 5 on Fig. 1.

Similar characters indicate like parts throughout the several figures of the drawings.

In the drawings, 10 is a base supporting a casing 11 having a cylindrical chamber 12 extending therethrough. The opposite ends of the casing 11 are closed by plates 13 having annular flanges 14 extending toward each other into the chamber 12, with their inner faces separated.

The end plates 13 are provided with out-

wardly extending brackets 15 on each of which is mounted a housing 16 having a bearing 17 therein for a revoluble shaft 18 centrally disposed within the chamber 12. 60

Keyed to the shaft 18 within the chamber 12 is a hub 19 having a web 20 disposed between the separated inner faces of the flanges 14. On the periphery of the web 20 are blades 21, extending outwardly from the web 20, parallel to the shaft 18 and adapted to be rotated by said shaft in an annular passage between the peripheries of the flanges 14 and the cylindrical wall of the chamber 12. 70

The end plates 13 are provided with stuffing boxes 22 surrounding the shaft 18 and preventing leakage from the chamber 12.

The end plates 13 are also provided with other stuffing boxes 23 surrounding a second shaft 24 made in two parts with an enlarged cylindrical portion 25 on one part positioned within an enlarged cup-shaped portion 26 on the other part, and secured thereto by means of a pin 27. 75

The flanges 14 have concavities 28 formed in the periphery thereof, into which a portion of the cup-shaped member 26 extends, the periphery of said cup-shaped member 26 closely fitting the wall of said concavity 28 and preventing leakage from the inlet 29 of the casing 11 to the outlet 30 thereof, or vice versa. 85

The members 25, 26 form a gate valve having a depression 31 therein, extending longitudinally of the axis thereof and adapted to receive the blade 21 as the shafts 18, 24 rotate. 90

Midway of the depression 31 the gate valve 25, 26 is cut away at 32 to receive the web 20 when the pump is in operation. 95

Preferably the blades 21 have a dovetailed groove 33 extending lengthwise thereof in which is disposed a bar 34 of hardened material. 100

While there is comparatively no wear upon the bar 34, under ordinary conditions, it is possible in pumping some kind of material, that the sediment therein might wear or otherwise injure the bar, and the dovetailed groove 33 is provided so that when a bar 34 becomes worn it may be removed and replaced by another. 105

Each housing 16 has superimposed thereon another housing 35 having a bearing 36 therein for the shaft 24. 110

The housing 35 is provided with a hinged

cover 37 covering an opening in the top of said housing through which the shaft lubricating ring 38 is adapted to be admitted.

The top of the housing 16 is similarly provided with an opening 39 through which the lubricating ring 40 for the shaft 18 may be admitted.

The shaft 18 extends through a gear casing 41 and has a pulley 42 secured thereto by which rotary movement may be imparted to said shaft 18. Within the gear casing 41 and keyed to the shaft 18 is a gear 43 meshing with a gear 44 secured to and rotating the shaft 24.

15 The gear casing cover 45 is provided with a packing ring 46 surrounding the shaft 18 and preventing leakage of lubricating oil from the gear casing.

16 The gear casing 41 is provided with a 20 plug 47 closing the filling opening in the top of the gear casing and is likewise provided with a plug 48 which closes an opening in the bottom of the gear casing, through which the oil may be drained from the casing when desired.

The housings 16 and 35 are respectively provided with plugs 49 and 50, closing openings through which the oil may be drained from said housings.

25 30 Oil may be admitted to the housing 35 through the opening in the top thereof, closed by the cover 36, and the housing 16 is adapted to be filled with oil through a pipe 51 extending from one wall thereof and closed by a plug 52.

The housings 16 and 35 respectively have pipes 53 and 54 extending therefrom, having gages of any suitable construction which show the level of the oil in said housings 40 16 and 35.

In order to prevent hammering when the pump is in operation, a pipe 55 is provided, extending from the chamber 12 at a point slightly in advance of one blade 21 when the 45 other blade 21 has just passed the inlet 29. This pipe 55 leads to the outlet 30 and has a valve 56 therein.

The valve 56 may be opened to any desired extent to permit the material being 50 pumped to flow from the discharge opening 30 into the chamber 12 to fill the space in advance of the right hand blade 21 when in the position shown in Fig. 4 of the drawings.

55 The outlet 30 has a pipe 57 extending upwardly therefrom, communicating with a closed chamber 58 which, for convenience of illustration, is shown much smaller than it would be in practice. As the material 60 being pumped is discharged into the opening 30, any surplus material which cannot be readily taken care of will enter the closed chamber 58 and compress the air therein.

This material will subsequently be forced 65 from the chamber 58 by the compressed air

therein to insure a continuous flow of material through the outlet 30 at all times.

The inlet 29 has a pipe 59 extending upwardly therefrom from which pipes 60 and 61 extend in opposite directions. The pipe 60 extends to an opening 62 communicating with an annular groove 63 in the cylindrical inner wall of one end plate 13, while a branch pipe 64 leading from the pipe 60 communicates with a passage 65 communicating with an annular groove 66 in the inner cylindrical wall of the other end plate 13.

The pipes 60 and 61 are provided with valves 67 and 68 regulating the flow of liquid through said pipes.

The pipe 61 leads to a passage 69 communicating with an annular space 70 in one end plate 13 and surrounding the shaft 24, this pipe 61 having a branch pipe 71 leading to a passage 72 communicating with a similar annular space 73 in the other end plate 13 and surrounding the shaft 24.

Opposite the annular grooves 63, 66, 70 and 73 are rings 74 within the stuffing boxes 22, 23 dividing the packing material in said boxes in two parts, 75, 76.

If the material being pumped leaks around the shafts through the packing parts 75 it will be drawn by suction through the pipes 60, 61, 59 into the inlet 29 and be carried with the rest of the material being pumped through the chamber 12 to the outlet 30.

With the bulk of the material leaking from the chamber 12 disposed of in this manner it is obvious that the pressure upon the outer part 76 of the stuffing box packings will be reduced to a minimum.

This construction will effectually prevent all leakage through the stuffing boxes and this is particularly desirable where materials like gasoline are being pumped.

The pipe 55 may be omitted and a valved passage in the casing provided for the said purpose.

By constructing a pump in the manner shown and described, the shafts carrying the piston and the gate valve therefor may be mounted in bearings on outboard brackets considerably removed from the piston blades 21, as no strain is brought to bear upon said blades. In small sizes the bearings may be mounted on outboard brackets but obviously in large sizes of pumps these bearings must necessarily be mounted directly upon supports provided therefor, independently of the pump casing.

Likewise, it is possible to locate the driving gears at points outside of the shaft bearings as indicated in Fig. 1.

In the drawings, two blades 21 are shown, with a single depression 31 in the gate valve, and consequently, the gears 43 and 44 are constructed so that the gate valve 25, 26 will

rotate twice to one revolution of the shaft 18. It is obvious, however, that the gears 43, 44 may be constructed of the same size and one or more blades 21 may be mounted upon the 5 shaft 18 with an equal number of depressions 31 in the gate valve.

It will be noted that the depth of the blades 21 is the same as the depth of the annular passage and that these blades 21 10 extend the full length of the annular passage. As a consequence, no strain is brought upon the blades except to force the material ahead of the blades as the shaft 18 rotates, and cause a continuous flow of the 15 material from the inlet 29 to the outlet 30.

Owing to the concavity 28 in the flanges 14, and the accurate fitting of the gate valve 25, 26 into said concavity 28, the material 20 being pumped cannot leak from the outlet 30 to the inlet 29.

It is believed that the operation and many advantages of the invention will be understood readily without further description.

Having thus described my invention, I 25 claim:

1. A rotary pump comprising a casing 30 having therein a cylindrical chamber provided with an inlet and an outlet passage extending therefrom; a revolute shaft; end plates on opposite sides of said casing having annular flanges extending toward each other with their end faces separated and provided with annular grooves surrounding said shaft; a member secured to said shaft 35 and positioned between said annular flanges; blades positioned between said annular flanges and the cylindrical wall of said chamber and secured to said member; a revolute gate between said inlet and outlet 40 provided with a depression to receive said blades during the rotation of said shaft; and a valved pipe leading to said inlet and through which any portions of the material being pumped and leaking into said grooves 45 may be withdrawn into said chamber.

2. A rotary pump comprising a casing 50 having therein a cylindrical chamber provided with an inlet and an outlet passage extending therefrom; end plates on opposite 55 sides of said casing having annular flanges extending toward each other with their end faces separated; a revolute shaft; a member secured to said shaft and positioned between the end faces of said annular flanges; blades positioned between said annular flanges and the cylindrical wall of said 60 chamber and secured to said member; a revolute gate valve between said inlet and outlet provided with a depression to receive

said blades during the rotation of said shaft; 60 a shaft for said gate valve; means for rotating both shafts in unison; pipes leading from the inlet to passages surrounding both shafts; and means in said pipes for controlling the flow of material therethrough. 65

3. A rotary pump comprising a casing having an annular passage with an inlet and an outlet communicating therewith; a revolute member in said casing provided with a blade adapted to travel in said passage; a 70 revolute gate valve between said inlet and outlet having a peripheral depression to receive said blade as it travels from the outlet to the inlet; means for rotating said member and gate valve in unison; and a passage 75 from the discharge side of said annular passage to said outlet.

4. A rotary pump comprising a casing having an annular passage with an inlet and an outlet communicating therewith; a revolute member 80 in said casing provided with a blade adapted to travel in said passage; a revolute gate valve between said inlet and outlet having a peripheral depression to receive said blade as it travels from the outlet 85 to the inlet; means for rotating said member and gate valve in unison; and a valved passage from the discharge side of said annular passage to said outlet.

5. A rotary pump comprising a casing 90 having a continuous annular passage with concentric inner and outer walls and of equal width throughout with an inlet and an outlet closely adjacent thereto and communicating therewith; a revolute member 95 in said casing provided with a blade extending the entire width of said passage and adapted to travel therein, said blade having a broad inner face fitting the inner wall of said passage; a revolute gate valve between 100 and adjacent to said inlet and outlet having a peripheral depression the same length as said blade and adapted to receive said blade as it travels from the outlet to the inlet, said gate valve consisting of a cylindrical 105 member having said depression formed therein and fitting into the bore of another cylindrical member having a long opening in the wall thereof opposite said depression, the two parts of said valve being secured 110 together and each having a shaft extending from the closed end thereof; and means for rotating said member and gate valve in unison.

Signed by me at 746 Old South Bldg., 115 Boston, Mass., this 18th day of July, 1923.

JUSTUS R. KINNEY.
